UNITED STATES PATENT OFFICE.

A. R. T. MILLER, OF ST. CLAIR HEIGHTS, MICHIGAN.

CIGAR-CUTTER AND MATCH-IGNITER.

SPECIFICATION forming part of Letters Patent No. 710,792, dated October 7, 1902.

Application filed November 4, 1901. Serial No. 80,993. (No model.)

To all whom it may concern:

Be it known that I, A. R. T. MILLER, a citizen of the United States, residing at St. Clair Heights, county of Wayne, State of Michigan, have invented a certain new and useful Improvement in Cigar-Cutters and Match-Igniters; and I declare the following to be a full, clear, and exact description of the invention, such as will enable others skilled in the art to which it pertains to make and use the same, reference being had to the accompanying drawings, which form a part of this specification.

My invention relates to a cigar-cutter and match-igniter; and the object of my improvement is to provide an improved apparatus by which a cigar may be cut and in the same operation a match withdrawn from a magazine and ignited.

Referring to the accompanying drawings, Figure 1 is a perspective of an apparatus embodying my invention. Fig. 2 is a vertical section. Fig. 3 is a rear elevation. Fig. 4 is a detail view of a part of the match-delivering apparatus. Fig. 5 is a perspective similar to Fig. 1, a part being broken away to show the interior construction. Fig. 6 is a plan view of the lower portion of the base and the apparatus attached to said base.

30 A is the base of the machine.

B is the casing.

C is the magazine in which the matches are put to be delivered one by one through the machine.

35 C' is a movable plate forming the back plate of the magazine C. The plate C' is pivoted to the side plates of the casing at its upper edges at c' c', as shown most distinctly in Fig. 5.

C² is a hanger extending downward from the 40 movable plate C' to a point just above the base A.

c is a spring acting to press the standard C² forward, and therefore also the plate C'.

D is the delivery-passage for the matches. 45 This passage is between the front plate of the casing and the lower end of the movable back plate C'. When the plate C' is in its forward position, the lower end of the passage D is closed, as shown in Fig. 4, and the upper end 50 of said passage is opened just enough to permit the presence of a match therein. The passage D is slightly enlarged toward its lower

end up to a point a short distance above its lower end. It is then contracted to its lower end, so that it will be completely closed when 55 the plate C' is moved forward.

E is a rod passing through an aperture in the rear of the base A and then branching, forming two parallel forks e e, (see Fig. 6,) which forks pass through guiding-apertures 60 in the front of the base.

E' is a lug rising upward from the rod E through an elongated slot in the top of the base A.

E² E² are springs acting to force the rod E 65 to its rearmost position.

E³ is a knife extending between the forks e e and secured thereto.

a represents holes in the top of the base A, through which the end of the cigar is inserted 70 to be cut.

The knife E³ passes along the bottom of the top of the base A beneath the holes E, acting to cut off the end of a cigar in one of the said holes.

75 F is a shaft resting in bearings of the casing B, toward the lower part of said casing. The shaft F is movable longitudinally in its bearings, and a coil-spring f² is provided, which acts to force the shaft F yieldingly toward one side of said casing.

f is a handle upon the end of the shaft F, outside the casing B, by which the shaft F may be rotated.

F' is a cam on the shaft F, near the center 85 thereof.

F² F² are arms upon the shaft F.

F³ is a horizontal plate extending between the outer ends of the arms F² F².

f³ is a groove in the upper surface of the 90 plate F³, adapted to receive a single match. The groove F³ is closed upon the end adjacent to the spring f² and is open at the other end.

F⁴ is a sector having a roughened or corrugated surface. The sector F⁴ is opposite 95 the open end of the groove F³.

I is a cam in the shape of a sector, having the same center as the sector F⁴ and adapted to act against one of the arms F² to force the shaft F and apparatus thereon against the 100 action of the spring f².

G G are vertically-extending plates located between the side plates of the casing B at the front of the apparatus and having their up-

per edges curved, so as to receive and retain a match. The side of the casing B is bent outward, as indicated at H, directly opposite the lower portion of one of the upper edges 5 of the plates G.

h is an aperture formed through the side of the casing at the lower edge of one of the side plates thereto at the lower end of the bent-out portion H.

10 The operation of the above-described device is as follows: The magazine C is filled with matches, all having their igniting ends toward the side which is away from the observer in Figs. 1, 2, and 5. The rod E being 15 forced to its rearmost position by the springs E² E² turns the shaft F until the arms F² and the cam F' are in the position shown in full lines in Fig. 2, at which position the groove f³ is directly below the lower end of 20 the delivery-passage D. At this position of the rod E the lug E' contacts the hanger C², forcing it backward against the action of the spring c and opening the passage D, allowing the match to drop therefrom into the 25 groove f³. When the arms F² F² are in their vertical position, holding the grooves F³ beneath the lower end of the delivery-passage D, the cam I has forced the shaft F to its farthest limit toward the observer in the position shown in Figs. 1, 2, and 5.

30 M is a swinging plate L-shaped in cross-section and extending from one side plate to the outer, pivoted to said plate so that it shall normally extend under the lower end of the 35 passage D, so that in case said passage should not be otherwise closed it will in any case be closed by the plate M. Said plate M is contacted by the carrier-plate F³ and swung backward thereby when the carrier-plate is 40 in position to receive a match.

45 The end of a cigar is pressed in one of the openings a, and the handle f is drawn forward, turning the shaft F, the cam F' acting against the lug E' to press the rod E forward, carrying the knife across the lower ends of the holes a and cutting the cigar. When the rod E commences its forward movement, it is drawn away from the hanger C², allowing the spring c to press said hanger and the 50 plate C' forward, closing the lower end of the delivery-passage D. The match in the groove f³ is carried forward, the spring f² forcing the shaft F in the direction of its length toward the sector F⁴ as the cam I narrows, and 55 thereby forcing the igniting end of the match against the rough surface of the sector F⁴, causing the match to ignite. The lower end of the cam I is again carried outward, carrying the match away from said sector when 60 the groove f³ comes below the lower end of the front plate of the casing B, as indicated in dotted lines in Fig. 2. The ignited match drops out of said groove upon the upper edges of the holding-plates G, the burning end of 65 the match comes opposite the bent-out portion H of the side plate and just above the

notch h, and the side plates of the casing come opposite the ends of the match, shielding the same and preventing the flame from being extinguished by accidental drafts, while 70 the aperture h supplies sufficient air for its free combustion. The match-stick resting upon and across the two holding-plates G G is in a position to be grasped by the fingers without danger. It will be observed that not 75 only is the match carried some distance from the magazine C before it is ignited, but the magazine is completely closed at this time, so that there is no danger of the matches still remaining in the magazine becoming ignited. 80 The movement of the back plate C' agitates the matches in the magazine C and causes them to all lie accurately in line.

What I claim is—

1. The combination of a magazine for containing matches, a shaft mounted in bearings and adapted to slide longitudinally therein, a carrier-plate mounted upon said shaft adapted to receive a match from said magazine, a sector having an igniting-surface located opposite one end of said carrier-plate, means for turning said shaft, means for pressing said shaft toward said sector during its rotation and a cam arranged to actuate said shaft to move said plate away from said 90 sector.

2. In a match-delivering apparatus, the combination of a magazine for containing matches provided with a movable side held in its position adjacent to the other sides by 100 a yielding pressure, an oscillating shaft parallel to said movable plate, a carrier-plate mounted on said shaft and a spring-actuated means for retracting said carrier-plate adapted to actuate the movable side of the magazine. 105

3. The combination of a magazine for containing matches, a delivery-passage from said magazine, a movable side to said magazine held yieldingly in position to close said passage, a reciprocating carrier adapted to receive a match through said passage when in its retracted position, a spring-actuated means for retracting said carrier adapted to move said movable side to open said passage. 110

4. The combination of an oscillating shaft, a plate for receiving and delivering a match mounted on said shaft, a cigar-cutting mechanism, a cam upon said shaft engaging the cigar-cutter to actuate the same when said shaft is oscillated, a spring acting to press the reciprocating cigar-cutter backward and thereby to retract said plate and means for oscillating said shaft against the action of said spring. 120

5. The combination of a casing having extensions of the side plates that constitute the casing, match-holding plates located between said extensions, means for withdrawing a match from said casing, igniting it and depositing it upon said holding-plates between said side extensions, one of said plates being 125

bent outwardly and inwardly adjacent to the position of the ignited end of said match when on said holding-plates.

6. The combination of a casing having extensions of the side plates that constitute the casing, match-holding plates located between said side plates, means for withdrawing a match from said casing, igniting it and depositing it upon said holding-plates between said extensions, one of said extensions being bent outwardly and inwardly adjacent to the

position of the ignited end of the match when on said holding-plates, and a notch cut through said side plate at its lower edge and at its bent-out portion.

In testimony whereof I sign this specification in the presence of two witnesses.

A. R. T. MILLER.
